UNITED STATES PATENT OFFICE.

JOSEPH BIJUR, OF NEW YORK, N. Y., ASSIGNOR TO BIJUR MOTOR LIGHTING COMPANY, OF NEW YORK, N. Y., A CORPORATION OF NEW YORK.

ENGINE-STARTING APPARATUS.

1,095,696.

Specification of Letters Patent.

Patented May 5, 1914.

Application filed March 13, 1912. Serial No. 683,426.

To all whom it may concern:

Be it known that I, JOSEPH BIJUR, a citizen of the United States, residing at New York city, in the county of New York and State of New York, have invented certain new and useful Improvements in Engine-Starting Apparatus, of which the following is a full, clear, and exact description, such as will enable others skilled in the art to 10 which it appertains to make and use the same.

This invention relates to starting apparatus, and with regard to the more specific features thereof, to means for starting internal combustion engines.

One of the objects of this invention is to provide practical and easily operated means for starting a source of power.

Another object is to provide means of the 20 above type of simple and durable construction peculiarly adapted for use in connection with internal combustion engines.

Another object is to provide means of the 25 above type which shall be convenient in control and whose action is automatic.

Other objects will be in part obvious and in part pointed out hereinafter.

The invention accordingly consists in the features of construction, combinations of elements and arrangement of parts will be exemplified in the construction hereinafter set forth, and the scope of the application of which will be indicated in the following claims.

35 In the accompanying drawings, wherein are shown one or more of various possible embodiments of the several features of this invention, Figure 1 is a diagrammatic view of starting apparatus; Fig. 2 is a detail view 40 of a magnetically controlled braking device; Fig. 3 is a sectional elevation of a resistance-varying and circuit-completing device; Fig. 4 is a diagrammatic plan of another form of starting apparatus having various features 45 in common with that shown in Fig. 1; Fig. 5 is a detail view of a magnetically controlled brake; Fig. 6 is a diagrammatic plan of another form of starting apparatus; Fig. 7 is a sectional elevation of a magnetically 50 controlled resistance-varying and circuit-completing device; and Fig. 8 is a detail view of a magnetic brake.

Similar reference characters refer to similar parts throughout the different views of the drawings.

Referring now to Fig. 1 of these drawings, there is shown an engine 1, preferably of the internal combustion type and comprising a crank-shaft 2, on which is mounted a fly-wheel 3 or other driven member. The face of this wheel is preferably slightly crowned, as indicated at 4, for a purpose hereinafter described. Driven from shaft 2, as by gears 5, is a countershaft 6, which in turn drives through gears 7 an electric generator 8 provided with a shunt field 9. Leadings from this generator are the mains 10 and 11, in the former of which is placed a main switch 12 of the well-known type, comprising a voltage coil 13 and a series coil 14 so wound and connected as to attract and close the contact member 15 upon the voltage reaching a value suitable for charging the storage-battery 16, connected as shown.

Mounted adjacent the member 3, in suitable bearings 17, is a shaft 18 having formed thereon right-hand and left-hand threads as shown. Upon these threaded portions are respectively fitted members 19 and 20, preferably formed of case-hardened steel in the general conical form shown and so shaped as upon being forced toward one another by a suitable turning of the shaft, to grip therebetween and be wedged into contact with the outer surface of member 3. This wedging action substantially precludes slipping and is attained by the inclination or pitch of the coacting threads upon the inner surface of the members and the outer surface of the shaft. The latter member is 90 driven by gear 21 and pinion 22 from a motor 23 and this gearing as well as the ratio of the effective diameters of the conical members to the effective diameter of member 3 are so proportioned that one revolution of the member 3 or crank-shaft of the engine will correspond to about thirty of the armature shaft. Coacting with the members 19 and 20 is a swinging member 24 provided with a pair of arms 25 and 26 normally urged by a spring 27 against the outer surfaces of the cones, which are preferably flattened as indicated at 28. Swinging member 24 is secured to the pin 29, jour-

naled in the frame of the electro-magnet 30, and the armature 31 of this magnet is also fast upon this pin and hence controls the position of member 24, the attraction of the magnet acting in opposition to the force of spring 27.

The solenoid 30 is connected across the mains 10 and 11 at a point on the generator side of the main switch 12 and is wound as a voltage coil. It will thus be seen that upon the engine being started the generator will immediately build up, thus enabling magnet 30 to attract its armature 31 and swing member 24 away from the threaded members 19 and 20.

Connected across the battery 16 is a voltage solenoid 32, the circuit of which is controlled by a swinging contact 33, conveniently positioned as upon the steering post 20 of an automobile. This member is locked in normal open-circuit position by a swinging segment 34, controlled by the spark lever 35 in such manner that the latter must be swung to spark-retarding position before 25 the circuit can be completed at 33. It may also be noted that as the spark is advanced subsequent to the starting of the engine, this segment automatically throws lever 33 into open-circuit position. The circuit, comprising solenoid 32, is preferably automatically broken at another point as the conductors comprising the same have serially connected therewith a pair of coacting contacts 36 and 37, the 30 latter being mounted upon the swinging member 24 and insulated therefrom, and the former being fixed in such position as to contact therewith when the member is swung upwardly by spring 27. It will thus 35 be seen that as the generator is started the controlling circuit is automatically broken at this point by the attraction of the armature 31.

Motor 23 is provided with a series field 45 winding 38 and a shunt field winding 39 and the circuit from the former leads to a fixed insulated plate 40, best shown in Fig. 3 of the drawings. This plate is mounted upon the casing of the solenoid 32, which is 50 provided with a core or armature 41 so shaped as to form a magnet of the so-called iron-clad type. Threaded upon the upper end of this magnet is a cap 42, which contacts with a piston 43 secured to the core to 55 form a dash-pot, the inlet of air being permitted by a passage 44 controlled by a ball valve 45. The lower end of core 41 is secured to a movable pressure-plate 46, between which and the plate 40 is a pressure- 60 controlled variable resistance medium 47, preferably comprising a set of carbon disks. These plates are insulated from their support but are provided with the pairs of contacts 48, adapted after complete compres-

sion of the medium 47 to form a shunt about 65 the same and eliminate its ultimate resistance. Secured to the plate 40 and insulated therefrom is a contact 49, adapted to coact with a contact 50 mounted upon and connected with the plate 46, and these contacts 70 are positioned closely adjacent one another so that even a slight movement of core 41 from its completely depressed position will close the circuit at this point, further movement of the core being permitted by the 75 spring formation of the arm 51 on which the contact 49 is mounted. From contact 49 a conductor 52 leads to one side of the battery and a conductor 53 leads from the other side of the battery to the terminal of the 80 motor at which the shunt coil 39 is connected, the remaining connection of this coil being with the plate 46.

The operation of the above-described embodiment of this invention is substantially 85 as follows:—Assuming that it be desired to start the engine 1 as of an automobile, the spark-lever is first swung into the full line position, thus retarding the spark, and lever 33 is then thrown into the circuit-completing 90 position shown. The current is thus led from the storage-battery through the voltage solenoid 32, the contacts 36 and 37 being in engagement, due to the deenergization of the solenoid 30. Solenoid 32 will 95 immediately attract core 41, and at the start of its movement will bring contacts 49 and 50 into engagement, thus leading current through the motor from the battery in series with the resistance medium 47, which is 100 substantially at its full value. The core 41 in continuing its movement gradually compresses this resistance and finally shunts it altogether, this action being cushioned by the dash-pot arrangement above described. 105 The motor will be started as soon as contacts 49 and 50 are brought into engagement and will drive the shaft 18 in such direction as to force the members 19 and 20 toward one another, the latter being frictionally 110 held against rotation by the pressure of the arms 25 and 26. Just as the flattened portions 28 pass from these arms the conical members are in full engagement with the then stationary member 3 and the reaction of the 115 latter wedges the parts securely into engagement. At this stage the members 19 and 20, which can travel no farther upon their threads, turn with the shaft 18 and the various parts are so proportioned and timed that 120 just at this point the resistance medium 47 is shunted and the motor exerts full power. Through the speed-reducing gearing above described the fly-wheel 3 is immediately rotated and the engine started, and by its action in driving the members 19 and 20, they 125 travel in a reverse direction on their threads and move out of operative position toward

that indicated in full lines in Fig. 1 of the drawings. The starting of the engine causes generator 8 to energize solenoid 30 and withdraw the swinging arms 25 and 26 from operative position as well as break the circuit of solenoid 32, unless the latter has already been broken by the advancing of the spark-lever as above described. As solenoid 32 is deenergized the weight of the parts 10 immediately cuts in resistance 47 and then breaks the circuit of the motor at contacts 49 and 50. If the parts still tend to spin by their inertia, the cones 19 and 20 are not again thrown toward the wheel 3, as, the 15 arms 25 and 26 being withdrawn, they turn freely with shaft 18. In this manner any hunting action or tendency of the conical members to move back and forth into and out of operative position after the engine 20 is started is entirely avoided.

In Fig. 4 of the drawings is shown a different embodiment of certain features of this invention and in this apparatus the engine 1 drives a member 54, which may serve 25 as the fly-wheel and is provided with gear teeth 55. Mounted adjacent this member, in the bearings 56, is a shaft 57, having a portion 58 upon which is threaded a pinion 59. Secured to this pinion 59 are a collar 60 and 30 a leather disk 61, these parts being adapted to travel as a unit upon the member 57. There is also threaded upon the latter member a nut 62 tied to the collar 60 by a flat spring 63 in such manner that this nut will 35 travel with the collar, and the spring 63 tending to force these parts toward or away from one another will take up any back lash or looseness in the threads and prevent an undesirable spinning action. The shaft 58 40 is driven by gears 21 and 22 from a motor 23 as in the apparatus heretofore described. The connections and controlling mechanism of this motor are also substantially identical with the corresponding parts of the first 45 described apparatus, but the circuit of solenoid 32 is closed in the first instance by a push-button 64 conveniently positioned, as on the steering-post of an automobile. This circuit, furthermore, leads through the 50 spark-lever 65 and a coacting contact plate 66 in such manner that it is necessary that the spark be retarded by movement of the lever into full line position before the solenoid 32 can be energized. Resiliently urged 55 against the outer surface of collar 60, by spring 67, is one arm of a bell-crank lever 68, the remaining arm of which forms an armature for a solenoid 69 connected across the mains 10 and 11 on the generator side of the 60 main switch 12. This arm 68 exerts a braking action upon the threaded member until the pressure is relieved and the solenoid circuit broken by the energization of magnet 69. There is preferably secured to the outer

face of the member 54 a ring 70, flanged as 65 at 71, to project into the path of the leather disk 61.

The action of the above apparatus is closely similar to that first described, but the following features of its operation should 70 be noted:—If it be desired to start the engine 1, the spark is retarded and the circuit of solenoid 32 completed at 64, thus gradually starting the motor 23. This action throws the member 59 inwardly, as its rotation is retarded by the lever 68, and as the teeth come into mesh with the teeth 55, collar 60 passes out from under arm 68. Pinion 59 travels fully into mesh with the gear 55, being held by the latter against rotation 75 until it has completed its travel and rests against a fixed collar 59^a on the shaft 57. At this stage the resistance in series with motor 23 is shunted and the motor exerts its full power to turn over the engine 1 and 80 start the same. As the engine is started it drives generator 8 to energize magnet 69 and the freely turning member 59 travels upon shaft 57 out of engagement with member 54, the motor being shut off, due to the 85 breaking of the solenoid circuit at contacts 36 and 37. If the shaft 57 is still spinning as the member 59 withdraws into the inoperative position shown, it will not throw the latter again into mesh as it will spin with 90 the shaft, due to the continued retraction of lever arm 68 and the nice fitting of the threads brought about by the action of spring 63. The return of pinion 59 into mesh is further prevented by the action of 95 the flange 71 engaging the disk 61, which engagement, with the engine running, would be of itself sufficient to cause member 59 to be so rotated as to again recede from member 54. It is to be understood, however, that this 100 engagement between the disk 61 and flange 71 is not sufficiently positive to prevent the parts passing into operative relation when the engine is started, as disk 61 will yield in 105 passing the then stationary flange. 110

In Fig. 6 of the drawings, there is shown apparatus which also embodies certain features of this invention. In this case the engine and its fly-wheel, together with the parts immediately coacting with the latter, 115 are substantially identical with the corresponding parts of the apparatus depicted in Fig. 1. The motor 23 is here connected through a conductor 72 and a contact member 33 to one side of the battery 16, which 120 may be charged from a generator driven from the engine if desired. The remaining motor lead passes through a series field 73 and resistance medium 74 to the opposite battery terminal. Also connected across the 125 battery is a circuit comprising a solenoid 75 and a magnet 76 in series one with another, this circuit being formed in part by the con-

ductor 72 and hence being dependent for its completion upon the contact member 33. Solenoid 75 controls resistance 74, and by means of the device shown in Fig. 7 of the drawings, which, in its mechanical elements, is substantially identical with that shown in Fig. 3 already, the corresponding parts are accordingly correspondingly lettered and their action will be clear. The magnet 76 controls the position of a bell-crank braking lever 77, which is normally retracted by spring 78 and thrown into braking position against the cones 19 and 20 as the magnet is energized. Lamps 79 may be connected as shown.

Considering the action of this apparatus in starting a stationary engine, the circuit is closed by contact member 33 as already described. This action completes a circuit through the motor 23, the shunt field 39 being fully energized and the series field 73 being connected through the resistance 74. The closing of the circuit, moreover, energizes solenoid 75, which gradually compresses and ultimately shunts resistance 74, and the magnet 76 is also energized with the closing of the circuit to bring about a braking action on the cones until they have passed into engagement with the member 3, as already described. When the engine is started, it, as previously set forth, tends to throw the cones out of operative relation, and as the spark is advanced by lever 35, the circuits of motor 23 and of solenoids 75 and 76 are broken, thus permitting the cones to reach their outward limit of travel and prevent any tendency to again drive them into engagement with member 3.

It will thus be seen that there is herein described apparatus in which the several features of this invention are embodied, and which apparatus in its action attains the various objects of the invention and is well suited to meet the requirements of practical use.

As many changes could be made in the above construction and many apparently widely different embodiments of this invention could be made without departing from the scope thereof, it is intended that all matter contained in the above description or shown in the accompanying drawings shall be interpreted as illustrative and not in a limiting sense.

Having described my invention, what I claim as new and desire to secure by Letters Patent is:

1. In apparatus of the class described, in combination, an engine, a member driven by said engine, a source of power, and means comprising a member driven from said source of power adapted to move said second member upon being so driven into operative relation to said first member and drive the same and upon being driven from said en-

gine automatically to move out of operative relation to said first member.

2. In apparatus of the class described, in combination, an internal combustion engine, a member driven by said engine, a source of power, a rotatable member, and means driven from said source of power adapted to move said rotatable member into operative relation to said first member and drive said first member through said rotatable member to start said engine.

3. In apparatus of the class described, in combination, an engine, a member driven by said engine, a source of power, a member driven thereby and adapted to be driven by said first member, and means adapted upon said second member being so driven to move it out of operative relation to said first member to disengage thereby said engine and said source of power.

4. In apparatus of the class described, in combination, an internal combustion engine, a member driven by said engine, a source of power, a rotatable member driven from said source of power, and means mounting said rotatable member adapted upon the same being driven from said source of power to move it into operative relation to said first member and drive said engine and adapted upon said engine being started to move said rotatable member out of operative relation to said first member.

5. In apparatus of the class described, in combination, an engine, a member driven by said engine, a source of power, a rotatable member, a supporting member driven from said source of power and having said rotatable member threaded thereon, said threaded member being positioned to move said rotatable member into operative relation to said first member and start said engine and means adapted to cause said rotatable member to advance along said supporting member upon the latter being driven from said source of power.

6. In apparatus of the class described, in combination, an engine, a member driven by said engine, a source of power, a rotatable member, a supporting member driven from said source of power and having said rotatable member threaded thereon, said threaded member being positioned to move said rotatable member into operative relation to said first member and start said engine and means adapted to cause said rotatable member to advance along said supporting member upon the latter being driven from said source of power, said rotatable member being formed to frictionally engage and drive said first member.

7. In apparatus of the class described, in combination, an engine, a member driven by said engine, a source of power, a rotatable member provided with a right hand thread and a left hand thread, a pair of

members respectively mounted upon said threaded portions and positioned to grip and drive said first member upon said threaded member being turned, and means adapted to drive said threaded member from said source of power.

8. In apparatus of the class described, in combination, an engine, a member driven by said engine, a source of power, a rotatable member provided with a right hand thread and a left hand thread, a pair of members respectively mounted upon said threaded portions and positioned to grip and drive said first member upon said threaded member being turned, means adapted to drive said threaded member from said source of power, and means adapted to retard the rotary movement of said pair of members as said threaded member is driven.

9. In apparatus of the class described, in combination, an engine, a member driven by said engine, a source of power, a rotatable member provided with a right hand thread and a left hand thread, a pair of members respectively mounted upon said threaded portions and positioned to grip and drive said first member upon said threaded member being turned, and means adapted to drive said threaded member from said source of power, the members of said pair being provided with inclined surfaces to engage said first member.

10. In apparatus of the class described, in combination, an engine, a member driven by said engine, a source of power, a rotatable member, and a supporting member driven from said source of power and having said rotatable member threaded thereon, said threaded member being positioned to move said rotatable member into operative relation to said first member and start said engine upon being driven from said source of power, said rotatable member being formed to frictionally engage and drive said first member, said member being formed to provide an inclined surface for engagement with said first member.

11. In apparatus of the class described, in combination, an engine, a member driven by said engine, a source of power, a rotatable member, a supporting member driven from said source of power and having said rotatable member threaded thereon, said threaded member being positioned to move said rotatable member into operative relation to said first member and start said engine upon being driven from said source of power, and means tending to retard the rotary movement of said member upon said threaded member.

12. In apparatus of the class described, in combination, an engine, a member driven by said engine, a source of power, a rotatable member, a supporting member driven from

said source of power and having said rotatable member threaded thereon, said threaded member being positioned to move said rotatable member into operative relation to said first member and start said engine upon being driven from said source of power, means tending to retard the rotary movement of said member upon said threaded member, and means adapted automatically to render inoperative said retarding means.

13. In apparatus of the class described, in combination, an engine, a member driven by said engine, a source of power, a rotatable member, a supporting member driven from said source of power and having said rotatable member threaded thereon, said threaded member being positioned to move said rotatable member into operative relation to said first member and start said engine upon being driven from said source of power, means tending to retard the rotary movement of said member upon said threaded member, and means adapted automatically to render inoperative said retarding means upon said engine being started.

14. In apparatus of the class described, in combination, an engine, a member driven by said engine, a source of power, a rotatable member provided with a right hand thread and a left hand thread, a pair of members respectively mounted upon said threaded portions and positioned to grip and drive said first member upon said threaded member being turned, means adapted to drive said threaded member from said source of power, means adapted to retard the rotary movement of said pair of members as said threaded member is driven, and means adapted automatically to release said retarding means on said engine being started.

15. In apparatus of the class described, in combination, an engine, a member driven from said engine, a member adapted to engage and drive said first member to start said engine, and means adapted to drive said second member and wedge it into operative relation to said first member.

16. In apparatus of the class described, in combination, an engine, a member driven from said engine, a member adapted to engage and drive said first member to start said engine, and means adapted to drive said second member and wedge it into frictional engagement with said first member.

17. In apparatus of the class described, in combination, an engine, a member driven from said engine, a member adapted to engage and drive said first member to start said engine, and means so mounting said second member as to wedge it into operative position by the reaction of its driving force on said first member.

18. In apparatus of the class described, in combination, an engine, a member driven from

- from said engine, a source of power, a member adapted to engage and drive said first member to start said engine, a shaft driven from said source of power and having said 5 second member threaded thereon and so positioned as upon being driven relatively to said second member to move said second member into engagement with said first member and wedge it against the same by 10 the reaction of its driving force thereon and means tending to retard the rotation of said second member with respect to said first member.
19. In apparatus of the class described, in 15 combination, an engine, a member driven from said engine, a pair of members, means adapted to cause the members of said pair to approach one another and grip therebetween said first member, and means adapted 20 to drive said first member through said pair of members.
20. In apparatus of the class described, in combination, an engine, a member driven from said engine, a pair of members, means 25 adapted to cause the members of said pair to approach one another and grip therebetween said first member, and means adapted to drive said first member through said pair of members, the members of said pair 30 being of conical form with their smaller ends toward one another.
21. In apparatus of the class described, in combination, an engine, a member driven from said engine, a pair of members, a shaft 35 having a right hand thread and a left hand thread, the members of said pair being respectively mounted upon said threads and positioned to embrace a portion of said first member, and means adapted to drive said 40 shaft and force the members of said pair to grip said first member.
22. In apparatus of the class described, in combination, an engine, a member driven from said engine, a threaded shaft, a conical 45 member threaded thereon and positioned to be moved into engagement with said first member and drive the same as said shaft is turned, and means adapted to drive said shaft.
- 50 23. In apparatus of the class described, in combination, an engine, a member driven by said engine, a source of power, and means comprising a member driven from said source of power adapted to move said member upon being so driven and wedge the same into operative relation to said first member to drive said engine and upon being driven from said engine automatically to move out of operative relation to said first 55 member.
- 60 24. In apparatus of the class described, in combination, an engine, a member driven by said engine, a source of power, a rotatable member, and means driven from said source of power adapted to move said ro- 65 tatable member and wedge the same into operative relation thereto and drive said first member through said rotatable member to start said engine.
25. In apparatus of the class described, in 70 combination, an engine, a member driven by said engine, a source of power, and means comprising a pair of members driven from said source of power adapted to move the members of said pair toward one another 75 upon being so driven to grip said first member and drive the same and upon being driven from said engine to move away from one another out of operative relation to said first member.
26. In apparatus of the class described, in 80 combination, an engine, a member driven from said engine, a member adapted to engage and drive said first member to start said engine, and means adapted to wedge 85 said second member into operative position by the reaction of its driving force on said first member and to move it out of operative relation to said first member upon being driven thereby after the engine is started.
27. In apparatus of the class described, in combination, an internal combustion engine, a member driven by said engine, a member mounted for rotation and reciprocation, means for moving at will said second member rectilinearly into driving engagement 90 with said first member and for rotating said second member to rotate thereby said first member and said engine, and for effecting the disengagement of said members automatically when said engine has started.
28. In apparatus of the class described, in combination, an internal combustion engine, a member driven by said engine, a rotatable member, means for moving at will said second member axially into driving engagement with said first member and for rotating said second member to rotate thereby said first member and said engine, and for effecting the return axial movement of said 100 second member out of engagement with said first member automatically when said engine has started.
29. In combination, an internal combustion engine, a source of power, and normally 105 disengaged power transmitting means interposed between said engine and said source of power and permitting said engine normally to turn in either direction independent of said source of power, said parts being formed and mounted to be moved automatically into an operative connection between said engine and said source of power by the starting of said source of power.
30. In combination, an internal combustion engine, a source of power, and normally 110 disengaged power transmitting means interposed between said engine and said source of power and permitting said engine normally to turn in either direction independent of said source of power.

ent of said source of power, said parts being formed and mounted to be moved automatically into an operative connection between said engine and said source of power by the 5 starting of said source of power, and to be automatically returned to normal condition by the starting of said engine.

31. In combination, an internal combustion engine, a source of power, a pair of normally disengaged gears interposed between said engine and said source of power, and means actuated by the starting of said source of power adapted automatically to bring said gears into engagement and complete a 10 power transmitting connection between said engine and said source of power and to disengage said gears automatically to break said power transmitting connection as said engine is started.

20 32. In combination, an internal combustion engine, a source of power, a pair of normally disengaged gears interposed between said engine and said source of power, one of said gears being axially movable into and 25 out of engagement with a second gear, and means actuated by the starting of said source of power adapted automatically to shift said first gear axially into engagement with said second gear and complete a power transmitting 30 connection between said engine and said source of power and to disengage said gears automatically as said engine is started.

33. In combination, an engine, a threaded driving shaft, a driving member threaded 35 on said shaft and normally out of contact with said engine, and means coöperating with said shaft adapted automatically to move said member into contact with said engine as said shaft is started and automatically 40 to withdraw said member as said engine is started.

34. A starter for gas engines and the like, comprising in combination with a member operatively connected with the engine, a motor, 45 a driving member operated thereby and adapted to coöperate with and drive the other member but normally out of engagement therewith, and means adapted upon said motor being started automatically to move said driving member into engagement 50 with said first member.

35. A starter for gas engines and the like, comprising, in combination with a member operatively connected with the engine, a 55 driving member adapted to coöperate with and drive the other member but normally out of engagement therewith means tending to retard the rotation of said driving member, a rotatable shaft with which said driving member coacts to produce longitudinal movement relative to the shaft for automatically moving the driving member into driving engagement with the other member whenever the shaft is rotated, and a motor 60 for operating the shaft.

36. A starter for gas engines and the like comprising in combination with a member operatively connected with the engine, a motor, a shaft driven thereby, a driving member adapted to engage and drive the 70 engine member but normally out of engagement therewith and means tending to prevent rotation of said driving member, said driving member being mounted on the shaft and having screw threaded engagement 75 therewith whereby rotation of the shaft advances such driving member into engagement with the engine member.

37. A starter for gas engines and the like, comprising in combination with a member 80 operatively connected with the engine, an electric motor including its armature shaft, a screw threaded shaft in line with the armature shaft and driven thereby, a driving member adapted to engage and drive the engine member but normally out of engagement 85 therewith and means tending to impede rotation of said driving member, said driving member being mounted on the screw threaded shaft and having means for engaging the latter whereby operation of the motor advances the driving member into engagement 90 with the engine member.

38. A starter for gas engines and the like comprising, in combination with a gear 95 wheel operatively connected with the engine, a motor, a shaft driven by the motor and having screw threads for a portion of its length and a stop shoulder at one end of said threads, a pinion mounted on the 100 shaft and having a bore engaging said threads, for longitudinal movement relative to the shaft when rotated and means tending to impede rotation of said pinion, the rotation of the shaft advancing the pinion into mesh with the wheel and the subsequent rotation of the wheel when exceeding that of the shaft withdrawing the pinion from mesh.

39. In apparatus of the class described, 110 in combination, an internal combustion engine, a gear operatively connected with said engine, a second gear adapted to mesh with said first gear and normally disposed offset in an axial direction from its meshing position, a motor, and means adapted automatically upon said motor being started to move said second gear in an axial direction into mesh with said first gear and drive said first gear.

40. In apparatus of the class described, 120 in combination, an engine, a source of power, gearing between said engine and said source of power, means actuated by said source of power for engaging said gearing simultaneously with the starting of said source of power, and automatic means for throwing said gearing out of engagement when the engine has started.

41. A starter for gas engines and the like,

comprising in combination with a member operatively connected with the engine, a motor, a driving member operated thereby and adapted to coöperate with and drive the other member normally out of engagement therewith, and means comprising a threaded connection between a motor-driven shaft and the driving member adapted, upon said motor being started, to move said driving member automatically into engagement with said first member.

42. A starter for gas engines and the like, comprising in combination, a member operatively connected with the engine, a motor, a shaft driven thereby, a driving member rotated by said shaft and adapted to coöperate with and drive the first member, but normally out of engagement therewith, a threaded connection between said shaft and said driving member, and means for retarding the initial rotation of said driving member when said shaft is set in rotation whereby upon said motor being started said driv-

ing member is moved automatically into engagement with said first member. 25

43. In apparatus of the class described, in combination, an internal combustion engine, a gear operatively connected with said engine, a second gear adapted to mesh with said first gear and normally disposed offset 30 in an axial direction from its meshing position, and means comprising a threaded connection between said second gear and its driving shaft, and a device to retard the initial rotation of said gear whereby upon 35 said motor being started said second gear is moved automatically in an axial direction into mesh with said first gear and drives said first gear.

In testimony whereof I affix my signature, 40
in the presence of two witnesses.

JOSEPH BIJUR.
